STERILIZER FOR DENTAL HAND PIECES

Walter S. Behrens, Buffalo, N. Y.

Application October 29, 1938, Serial No. 237,732

3 Claims. (Cl. 21—90)

My invention relates in general to sterilizers and more particularly to sterilizers for dental hand pieces.

It is well known to those skilled in the art that it is the custom to sterilize dental hand pieces by the use of a disinfectant or germicide. It is well known, however, that when liquid is used as the sterilizing medium, the lubricant in the bearings of the hand pieces is removed in the act of sterilizing. This lubricant must be replaced in a convenient manner in order to prevent excessive and undue wear of the parts of the hand pieces. It is desirable, therefore, when using liquid as a sterilizing medium to also have a receptacle conveniently located containing oil for easily lubricating the mechanism.

I am aware that sterilizers of this general nature have heretofore been manufactured in the form of two separate glass bottles loosely mounted in a holder. The disadvantage of this form of device, however, is that the accumulation of pumice and other grinding materials which occurs on the inside of the bottle after a short time has a soiled appearance to the patient, and this accumulation which, in itself, is sterilized, is difficult to remove from the interior of the bottle because of the shape of the bottle and the constriction at the mouth thereof. Furthermore, I am aware that single-chambered sterilizers have been suggested which have been loosely supported by a hook engaging some part of the dental engine.

One of the principal objects of my invention has been to provide a sterilizer of this nature in which the two receptacles shall be constructed of metal so that any accumulation on the inside surfaces thereof shall not be visible to the patient.

Another object has been to provide receptacles so arranged that they will be permanently secured to each other.

Another object has been to provide such metal containers with screwthreaded caps at the bottom, each having a concave upper surface, such surface being so proportioned that it substantially meets and joins the interior surface of the receptacle, thus providing a smooth, interior surface which may be easily cleaned with or without the removal of the cap.

Furthermore, my receptacles are so formed as to provide a smooth, unrestricted, and open-mouth interior which permits easy cleansing.

Furthermore, since the receptacles of my device form an integral unit, it is possible to conveniently attach such unit in rigid manner to

the tray of a dental chair, or to any desired part of the dental equipment.

Other objects have been to provide a device of this nature which may be inexpensively manufactured; convenient to use; and attractive in appearance.

The above objects and advantages have been accomplished by the device shown in the accompanying drawing, of which:

Fig. 1 is a front elevation of my complete device.

Fig. 2 is a plan view, with a portion of the cover broken away.

Fig. 3 is a side, sectional elevation taken on line 3—3 of Fig. 1.

Fig. 4 is an end elevation of the fastening means.

My invention, in its preferable form, comprises a body part 5 which is preferably molded from any suitable material. This body part is so designed as to provide two receptacles 6 and 7 for the reception, respectively, of a suitable disinfectant and a lubricant. Each of the receptacles formed in the casting has, preferably, a cylindrical bore 10, thus providing an open mouth 11 of substantially the same diameter as the bore, whereby there will be no constriction at the mouth to interfere with the convenient use of the device.

Each of the receptacles 6 and 7 is open at its bottom end where it is provided with interior screwthreads 13 for the engagement of a cap 12 having suitable screwthreads formed on the projecting portion 14 thereof. The upper surface 15 of the cap is preferably concave and of such radius as to be easily cleaned, either while in the receptacle or when removed therefrom. The relative proportions of the cap and bore of each receptacle is such that the surface 15 of the cap substantially meets and joins the bore of the receptacle so that there is a substantially smooth, unbroken interior surface in each of the containers, which avoids pockets for the accumulation of sediment in the disinfectant and makes it possible to easily clean the device.

The cap 12 may be conical on its lower end so as to give to the device an attractive appearance and, when so constructed, I preferably provide finger tabs 16 thereon. These finger tabs may be two in number if desired and are, therefore, oppositely arranged, whereby each cap may be easily removed from the bottom of each container.

A pivoted cover 20 is provided for closing the upper ends of both containers 6 and 7. This

cover preferably is formed with a downwardly extending flange 21 which fits the general contour of the body of the device and it is hingedly attached to a pivot pin 22 which passes through a lug 23 formed at the back of the cover. Pivot lugs 24 are formed on the body 5 and arranged preferably back of each receptacle. The pivot pin 22 is designed to pass through these lugs, whereby the cover will be pivotally supported thereby.

Arranged at some convenient place upon the body, and preferably at the side of the receptacle 6, is formed a supporting pad 25 which provides means for securing any type of bracket 26 to the device. Any suitable bracket may be used in connection with my device, and its design will depend upon the place where the sterilizer is to be used. A very convenient location is at the edge of the usual porcelain instrument tray which is supported from beneath by a spider arrangement having radiating arms. The bracket shown, therefore, has a horizontally arranged arm 30 having two pairs of outwardly extending ears or tabs 31 and 32 at spaced distances, each pair of which being designed to be used with a clamp or strap 33. Each clamp or strap is held in place by means of screws 34, and the horizontal arm and clamp is so formed as to provide a recess 35 of the proper shape to fit the arm to which the bracket is to be attached. A downwardly extending arm 36 is provided on the bracket for cooperation with the pad 25, and this arm is secured to the pad by means of screws 37.

If desired, I may provide spring clips 40 near the top of each of the containers between which the hand piece may be slipped for temporarily holding the same in place in the sterilizer or lubricant.

Obviously, my device, because the receptacles are integral with one another, may be firmly and conveniently held in position on any part of the dental equipment without the possibility of tipping over the receptacle or spilling the contents thereof.

When the device is to be used, it is only necessary to raise the cover 20 and to insert the hand piece of the dental tool first in the disinfectant in the container 6, after which it can be immediately transferred to the receptacle 7 containing the lubricant. When my device is to be used for sterilizing a contra-angle hand piece, the same may be removed from the dental tool, if desired, and dropped into the sterilizer and then into the lubricant, my receptacles being of such depth that this operation may be conveniently accomplished.

Because of the opaque nature of the containers, it is obviously not necessary to so frequently clean the containers since the patient cannot see the condition of the interior. When cleaning it is, however, a very simple matter. It is only necessary to remove the cap at the bottom of each of the containers, one at a time, draining the liquid contained therein into a suitable receptacle, after which the interior of the receptacle may be easily and conveniently cleaned. Likewise, the concave surface 15 of the cap can also be easily cleaned. When made of metal, my device may be plated and polished so as to have a very attractive appearance.

While, in the preferred form of my invention, the receptacles are molded integrally in one cast-

ing, it is obvious that these receptacles may be separately constructed and secured together by any suitable means. Moreover, the bore in the cylinder may be varied somewhat from the cylindrical form shown and described and the mouth thereof may also be varied in shape. Furthermore, while I have shown the caps as being conical in shape, and having finger tabs or wings, it is obvious that these caps may be cylindrical, if desired, and provided with knurled surfaces. Other shapes may be used without affecting the utility of my device, and it is, therefore, obvious that these and other modifications may be made without departing from the spirit of my invention or the scope of the appended claims, and I do not, therefore, wish to be limited to the exact embodiment herein shown and described.

Having thus described my invention, what I claim is:

1. A sterilizer for dental hand pieces, comprising a one-piece body having two parallel, interspaced receptacle-forming bores of round and uniform cross section, extending entirely therethrough from top to bottom with bracket means on the side of the body for permanently mounting the same, individual liquid-tight bottom closures for the receptacle-forming bores independently removable for cleaning each bore, each closure being fitted into its respective bore and having a substantially concave sediment-collecting basin inwardly from the walls of the bore, and a cover common to both bores and mounted on the body to move clear of said bores, whereby upon removal of the closures, free access will be given to both bores through each end for cleansing the same.

2. A sterilizer for dental hand pieces, comprising a one-piece body having two parallel interspaced receptacle-forming bores of round and uniform cross section, extending entirely therethrough from top to bottom with bracket means on the side of the body for permanently mounting the same, individual liquid-tight bottom closures for the receptacle-forming bores independently removable for cleaning each bore, each closure being threaded into its respective bore and having a substantially concave sediment-collecting basin inwardly from the walls of the bore, said closure having its exterior bottom portion formed with a hand hold of relatively reduced proportions, and a cover common to both bores and mounted on the body to move clear of said bores, whereby upon removal of the closures, free access will be given to both bores through each end for cleansing the same.

3. A sterilizer for dental hand pieces, comprising a one-piece body formed of opaque material and having two parallel, interspaced receptacle-forming bores of round and uniform cross section, extending entirely therethrough from top to bottom with bracket means on the side of the body for permanently mounting the same, individual liquid-tight bottom closures for the receptacle-forming bores independently removable for cleaning each bore, each closure being fitted into its respective bore and having a substantially concave sediment-collecting basin inwardly from the walls of the bore, and a cover common to both bores and mounted on the body to move clear of said bores, whereby upon removal of the closures, free access will be given to both bores through each end for cleansing the same.
